UNITED STATES PATENT OFFICE

WALTER WOLFF, OF CHICAGO, ILLINOIS, ASSIGNOR OF ONE-FIFTH TO ROBERT H.
WENDT, OF CHICAGO, ILLINOIS

GARMENT SUPPORT

Application filed January 14, 1929. Serial No. 332,347.

The present invention relates to garment supports, and is particularly concerned with garment supports for closets and the like.

None of the garment supports of the prior art have been found capable of supporting any substantial weight of clothes without sagging, so that the coat or garment hangers slide down to the end of the cantilever or hanger arm, piling up at the end or sliding off at the end of the support. The sagging which is inherent in the prior garment supports of the cantilever type, renders them commercially impractical, and the prior devices have also been relatively expensive in construction, requiring special dies and machinery. Furthermore, the prior devices have not been adaptable to closets of various sizes and shapes, nor have they been capable of utilizing all of the closet space and at the same time giving free access to every garment and part of the closet.

One of the objects of the invention is the provision of an improved commercial form of garment support which is adapted to movably support a wardrobe of sufficient size to fill an ordinary closet, in such manner that the clothing is all accessible and so that the complete assembly may be moved out of the closet to give access to the floor space, shelves or hooks carried by the walls.

Another object is the provision of a garment support which is adaptable to closets of any shape or size, and the parts of which are reversible for use on the right-hand or left-hand side of the door.

Another object is the provision of a garment support of the class described, which is strong and durable and yet light enough in weight to be carried by the frame structure of the closet or door, and a garment support in which the inherent sag of the devices of the prior art has been eliminated.

Another object is the provision of a garment support which may be so cheaply manufactured that it will be within the means of a vast number of purchasers for use in homes, apartments, hotels and in every environment where economy of space is important.

Another object is the provision of a novel supporting bracket for devices of the class de-

scribed, which is adapted to be firmly secured to a door frame with a minimum of screws, and in such manner as to support an extremely heavy wardrobe.

Another object is the provision of a novel braking mechanism for garment supports of the class described, which is adapted to releasably hold the hanger arms in any adjusted position.

Another object is the provision of a novel garment support of the cantilever type which is lighter and stronger than the devices of the prior art and which may be constructed of a minimum of material.

Other objects and advantages of the invention will be apparent from the following description and from the accompanying drawings, in which similar characters of reference indicate similar parts throughout the several views.

Referring to the drawings, of which there are two sheets;

Fig. 1 is a view in perspective of my garment support;

Fig. 2 is a plan view of the garment support attached to a door frame;

Fig. 3 is a sectional view on the line 3—3 of Fig. 2;

Fig. 4 is an elevational view in partial section, showing a modified form of construction of the cantilever pivot;

Fig. 5 is a view in perspective and partial cross section, taken medially of the pivots of the hanger arms, showing the device for retaining the hanger arms in any adjusted position;

Fig. 6 is a sectional view on the line 6—6 of one of the hanger arms;

Fig. 7 is a sectional view taken on the line 7—7 of Fig. 5, looking in the direction of the arrows;

Fig. 8 is a plan view showing an installation in a closet having the door non-symmetrically located;

Fig. 9 is a plan view of an installation in a closet having its door at the end of the closet.

Referring to Figs. 1 and 2, 10 indicates in its entirety my garment supporting device, which preferably includes a supporting

bracket 11, a cantilever 12 and one or more hanger supporting arms 13 and 14. The bracket 11 is adapted to be secured to the wall of a closet in order to pivotally support the cantilever 12 and hanger arms 13 and 14 in proper position within the closet as shown in Figs. 8 or 9, and to permit the pivotal movement of the entire assembly of garment support and clothing outside of the closet so that all parts of the closet are readily accessible.

Referring to Figs. 8 and 9, the two installations illustrated are merely exemplary of conditions which may be readily met by using hanger arms of different lengths, and it is contemplated that with a limited supply of cantilevers and hanger arms of different lengths, any ordinary closet may be satisfactorily equipped with one of the garment supports.

Referring to Fig. 8, 15 indicates a closet having a door opening 16 non-symmetrically located at one end of the closet as is often the case, and the garment support 10 is therefore provided with arms 13 and 14 of unequal length. Thus the arm 13 is adapted to project backward into the rear end of the closet and utilize the space at this end of the closet, and at the same time, both of the arms 20 may be pivoted in such manner that the entire device may be swung out of the door 16. In any event, the hanger arms should be short enough to clear the doorway 16 when the cantilever is moved to the dotted line position in Fig. 8.

Referring to Fig. 9, the same device has been installed in a closet 17 having a door opening 18 at its end, and the hanger arms are shown at right angles to each other, leaving the longer arm 13 projecting into the interior of the closet. It will thus be observed that the wall of the closet may be provided with a plurality of hooks 19, with shelves 20 and the floor space may be utilized for trunks 21, and as the entire garment support may be pivotally moved outside of the closet, all of the floor space and wall space is readily accessible. Furthermore, the garments on the support are conveniently disposed for selection, or they may be moved to the outer dotted line position for the purpose of allowing the clothing to air. The clothes hangers 22 on the hanger arms 13 and 14 are merely indicated diagrammatically, as any form of coat hanger, pants hanger or other clothes hanger may be used.

One of the most important features of the present invention is the provision of a novel cantilever construction which is actually capable of supporting a considerable weight of clothing without sagging, a defect which is inherent in all of the devices of the prior art.

I am aware that sheet metal devices for holding garments have been constructed, and other devices have pivotal arms, but none of

the devices of the prior art have been commercially practical because of the inherent defect of the sagging of the arms. This sagging is generally the result of the light sheet metal construction, since it is necessary that the device be relatively light, or it is the result of the construction of the pivot employed in the devices of the prior art, since any looseness in the pivots or any bending in the arms is magnified at the end of the cantilever arm.

Another important feature of the present invention is the provision of a bracket for garment supports of the class described, which is capable of being firmly attached to a door frame or other part of the closet wall in such manner that it is capable of supporting the weight of the garment support and the clothes carried thereby, without sagging or without tearing loose from the wall. In order to accomplish this result, the bracket 11 has been constructed with a pair of attaching flanges 23 and 24 at right angles to each other and adapted to extend parallel to the portions of the wall adjacent a corner.

Each of the flanges 23 and 24 is provided with spaced apertures 25 preferably located in such position that the screws 26 will extend through the trim 27 into the stud 28, and the flanges 23 and 24 should be of substantial length to provide a substantial area of bearing surface against the corner of the door frame. It will thus be observed that when the bracket 11 is installed as shown in Fig. 2, and the parts are in the position of Fig. 2, the upper portion of the flange 23 will bear against the inside trim 27 and the only screw which is subjected to any outward pull is the lower screw in the bracket 23, the two screws 26 in the bracket 24 are subjected to a lateral thrust which they are well adapted to withstand, and this lateral thrust is principally taken by the flange 23 bearing against the trim 27.

When the parts of the hanger are disposed as shown in Fig. 9, the upper attaching screws are subjected to a lateral thrust which has a small component tending to pull the screws outward, while the lower screws 26 are not subjected to any substantial strain, since the lower part of the bracket tends to press against the corner. It will be evident that the particular bracket construction shown is capable of providing an extremely firm connection to a door frame or the like by means of a very few screws, and the present device may be installed by any layman or house owner not particularly skilled in the art, with the same success as a skilled carpenter, since the holes may be disposed; so that the screws furnished will have to be driven directly into the stud which constitutes the firmest part of the door frame, and since the right-angled flanges reinforce each other.

The bracket 11 is provided with a pair of

laterally projecting bearing members 29 and 30 preferably formed integrally with the bracket which may be constructed of cast iron, steel, aluminum or any other metal. In its cheapest form, the entire garment support 5 is constructed of cast iron, which may be coated with colored enamel or dipped in paint, but if desired, the entire device may be nickel plated or otherwise coated, to withstand corrosion, in the more expensive devices. 10

The bearing members 29 and 30 are preferably of substantial thickness in order that a substantial bearing surface may be provided, 15 and the bearings 31 and 32 comprise accurately formed cylindrical bores capable of receiving the pintle 33 with a relatively close fit. The pintle 33 comprises a cylindrical bolt of steel or iron having a head 34 and 20 adapted to be slid endwise into the bearings 32 and 33.

The cantilever 12 comprises a cast metal member which is preferably curved longitudinally at 35 in order that its outer end 36 25 may swing farther away from the door opening, clearing the door 37. Furthermore, the curvature of the cantilever 12 enables the user to locate a securing bracket on the interior of the closet and at the same time have the 30 hanger arms swing around the door frame to the outside of the closet. In some embodiments of my invention, the curvature of the cantilever arm may be eliminated.

In order that the hanger arm may resist 35 the torsional strain which is placed upon it when one of the hanger arms 13 or 14 is unequally loaded, I provide the cantilever with a plurality of longitudinally extending flanges 38, 39, 40 and 41, making the cantilever substantially cruciform in section in the embodiment shown. The upper and lower 40 flanges 38 and 39 are peculiarly adapted to strengthen the cantilever against bending strains caused by the weight of objects attached to the outer end of the cantilever at 45 the outer end of the cantilever at 36, while the lateral flanges 40 and 41 are adapted to further increase the strength of the arm against torsional strains, such as would be produced in the arm by the use of 50 arms of unequal lengths or by swinging of both of the hanger arms 13 and 14 to one side of the cantilever at the same time.

At each end of the cantilever 12, the lever is increased in width at 42 to provide a bearing portion 42 of substantial length transversely to the cantilever, and the bearing portion 42 is also provided with an accurately formed cylindrical aperture 43 extending from top to bottom and adapted to form a 55 close fit with the pintle 32.

By making the bearing portion 42 of increased length longitudinally of the bearing 60 43, the amount of play in the bearing is greatly reduced, eliminating any possibility 65 of sagging due to the pivotal connection at

the pintle 32. Furthermore, the provision of a closely fitting bearing and pintle is of great importance in the elimination of any sagging, and the provision of a relatively large area of bearing surface insures a pivotal support without sagging, for a long period of use. 70

If desired, the cylindrical portion 44 intermediate the bearings 43 may be removed as shown in Fig. 4, forming a cantilever end 75 which is bifurcated, having spaced bearings 43 formed in legs 45 and 46. The laterally projecting flanges 40 and 41 are also bifurcated and extended to the legs 45 and 46 to increase the strength of the cantilever. 80

At its opposite end 36, the cantilever 12 is bifurcated to provide a pair of bearing members 47 and 48 best shown in Figs. 5 and 7, and the bearing members 47 and 48 may be provided with a plurality of cylindrical bearing apertures 49, 50, 51 and 52 for supporting as many hanger arms 13 and 14 as are desired. 85 One of the bearing members 47 is provided with a threaded aperture 53 adapted to receive a screw bolt 54 for engaging a plate 55 which forms a friction device engaging the hubs 56 of the hanger arms 13 and 14 to retain them in any adjusted position. 90

The hanger arms 13 and 14 comprise elongated metal members which are also preferably formed of cast metal in order to economically provide the type of bearing and the strength which is required in a hanger arm. 95 Each hanger arm preferably includes a substantially cylindrical hub 56 which is provided with a transversely extending cylindrical aperture 57 adapted to closely fit a pintle 58, and the pintles 58 may comprise ordinary cylindrical steel bolts having heads 59 for determining their final position in the bearing. 100

As the pintles 58 and 32 are arranged vertically, they may always be disposed with their heads on top so that no other fastening means are required, particularly in view of 110 the fact that a close frictional fit is highly desirable to eliminate any possibility of looseness or sag at the pivots. The plate 55 comprises a plate of sheet metal having apertures 60 to receive the pintles 58 and sufficient space is provided between the bearing members 47 and 48 so that there is room for the plate 55 between one of the bearing members 47 and the hubs 56. The plate 55 may then be urged against the ends of the hub 115 56 by the screw bolt 54 constituting an adjustable friction device which will retain the hanger arms 13 and 14 in any adjusted position. Where such a friction device is not employed, the hanger arms will naturally 120 gravitate to the lowest position resulting from the installation of the bracket 11, and this position may not be the most desirable location of the hanger arms within the closet. 125

The friction device will also hold the arms 130

in the position to which they may be turned when swinging the cantilever in or out of the closet, and this is also very important as it is desirable that the arms be swung to such a point that the clothing will clear the door without rubbing or displacing the clothing on the hangers. The friction device thus renders the control of the garment support possible in both its permanent position in the closet and in the movement of the clothing in or out of the closet.

Referring to Fig. 5, it will be observed that the upper or body portion 61 of the hanger arms slopes slightly upward from the hub 56. This upward slope is purposely exaggerated in the drawing in order to illustrate this feature more clearly. When one of the hanger arms 13 or 14 is loaded alone, or when both hanger arms extend toward the same side of the cantilever 12, a slight amount of torsional flexibility in the cantilever arm 12 tends to slightly lower the outer end 62 of the hanger arm, and consequently it is desirable to have the body of the hanger arm slope slightly upward toward its outer end. The hanger arm is also provided with an upwardly extending stop 63 at its outer end for the purpose of preventing the hooks of the hanger from sliding off the arm, and if desired, the body 61 may have a plurality of notches 64 for locating the hooks of the hanger.

In order to provide a hanger arm having the requisite degree of stiffness, I form the arm with a longitudinally extending flange 65 best illustrated in Figs. 5 and 6, and the flange 65 may be tapered from the hub 56 to the outer end 62 of the arm, thus providing an arm of a maximum strength, without unduly increasing the weight of the structure which must always be supported by the cantilever 12.

It will thus be observed that the garment support described is capable of supporting an extremely heavy weight of clothing without any appreciable sag, and the clothing may be moved from the interior of the closet to the exterior of the closet for the purpose of giving access either to the closet or to the clothing, as previously pointed out.

The relatively stiff construction and the elimination of the sag which has been inherent in the devices of the prior art is the result of the peculiar construction of the present device comprising the stiff arms and the accurately formed and elongated bearing surfaces extending transversely to the arms. The supporting bracket is also peculiarly adapted to provide a firm mode of supporting the device on the wall of the closet, and the friction device is adapted to retain the hanger arms in any adjusted position to prevent the hangers from swinging against the wall of the closet or against the doorway.

While I have illustrated a preferred em-

bodiment of my invention, many modifications may be made without departing from the spirit of the invention, and I do not wish to be limited to the precise details of construction set forth, but desire to avail myself of all changes within the scope of the appended claim.

Having thus described my invention, what I claim is new and desire to secure by Letters Patent of the United States, is:

In a garment support, the combination of a metal bracket having a pair of flanges extending at right angles and a pair of bearings, with a hanger arm having a bearing adapted to be received between the bearings on said bracket, a pin extending through the bearings of said bracket and said arm to pivotally mount said arm on said bracket, laterally projecting and vertically projecting flanges on said arm to resist torsional strain, bearing flanges carried by the end of said arm and a pair of hanger arms each having a bearing located between said bearing flanges, said hanger arms being pivotally mounted on separate pins, a resilient plate engaging the ends of the bearings of said hanger arms, and adjustable means for regulating the amount of friction between said plate and hanger arm bearings.

In witness whereof, I hereunto subscribe my name this 11th day of January, 1929.

WALTER WOLFF.
